FLUID PRESSURE CONTROLLER DEVICE

Ernest G. McCauley, Dayton, Ohio

Original application January 31, 1928, Serial No. 250,919, now Patent No. 1,860,510, dated May 31, 1932. Divided and this application January 16, 1932, Serial No. 587,123. Renewed April 27, 1936

26 Claims. (Cl. 137—144)

This invention relates generally to a fluid pressure operated mechanism and especially to controlling means therefor. More particularly this invention relates to a controller for use in connection with fluid pressure operated devices and constituting a unit in fluid pressure systems.

This application is a divisional application of my co-pending application Serial No. 250,919, filed January 31, 1928, now Patent No. 1,860,510 10 issued May 31, 1932.

This invention has for one of its objects the provision of a controller device having means for independently or simultaneously actuating spaced fluid pressure operated devices and valve means 15 operated by said first-mentioned means for regulating the supply of fluid to working chambers of said fluid pressure operated devices.

A further object of my invention is to provide a unitary control device of this character in 20 which a universal control lever is adapted to control the operation of separate fluid pressure operated devices either simultaneously or independently of one another and to regulate the fluid pressure to said pressure operated devices. 25 A further object of my invention is to provide in a unitary control device of this character, a unit mounting for a universal control lever that is capable of being moved fore-and-aft, laterally in either direction, or any combination of these 30 movements, and for suitable connections associated with said lever for converting these movements to other devices.

Another object of my invention is to provide a novel combination of universal control lever and 35 frictional means for retaining or holding the lever in any position within its range of operation, and for consequently holding the devices connected to the control lever and operated thereby against undesired movement.

A still further object of my invention is to provide in a unitary control device of this character having valve means for controlling the fluid pressure supply, a universally movable control lever adapted for actuating a plurality of spaced valves 45 either simultaneously or independently of one another to establish communication between the source of supply and a plurality of spaced working chambers, said control lever being adapted to 50 actuate said valve means in any position within its range of universal operation while maintaining said communication, and means associated with said lever for retaining the valve means in open position during the universal movement of 55 said lever.

Fig. 1 is a side elevation of an airplane with my invention incorporated therein;

Fig. 2 is a part sectional side elevation view of the hand controller or control lever unit for the control units shown in Fig. 5;

Fig. 3 is an end elevation of the view shown in Fig. 8;

Fig. 4 is a partial end elevational view looking from the left of Fig. 8;

Fig. 5 is a schematic view showing the application of my invention in the control system for an airplane with parts of a control unit broken away;

Fig. 6 is a sectional view taken on the line 6—6 of Fig. 5;

Fig. 7 is a sectional view taken on the line 7—7 of Fig. 6; and

Fig. 8 is an enlarged fragmentary view of the operating valve device shown in Fig. 7.

Similar reference characters and numerals refer to similar parts throughout the several views of the drawings.

This type of fluid pressure mechanism may be applied to operate various devices; for illustration I have shown it installed in an airplane to provide a power control for controlling the ailerons and elevators, while it can also be applied to operate the rudder, stabilizer, retractable landing gear, and for adjusting the pitch of an adjustable pitch propeller, and contemplates the use of a controller or control lever unit to enable the control of the actuation of these devices either simultaneously or independently of one another, which controller comprises in accordance with this invention a single manually operable member adapted to effect the supply of fluid pressure to and its release from the working chambers of the power control units.

My invention is shown, by way of example, as installed in an airplane 10 for use as a supplementary control to the regular manual control installation, for operating and controlling the ailerons and elevators of the airplane, the ailerons 12 and the elevators 14 being connected to the control stick 16, as shown in Fig. 1, in the usual and well-known manner. The fluid pressure system, as shown in Fig. 1, consists of an air compressor 18 for forming the fluid pressure source, connected to a storage tank 20, which in turn is connected to a controller or control lever unit 22 for operating the control units 24 and 26, which are also connected to the ailerons 12 and elevators 14 respectively, all in a manner substantially as shown and described in my above-referred-to application.

The controller or control lever unit 22, best shown in Figs. 2 and 3, is operatively connected to an operating valve device that is associated with each of the power control units, and comprises a universal swiveling lever 28 and a fluid pressure supply valve 30 operated by said swiveling lever.

The two power control units 24 and 26 are operated by the single control lever 28, as will be hereinafter described, a universal swiveling action being necessary whereby the control lever may be moved forward or backward from a vertical normal position, also sidewise in either direction, or any possible combination thereof.

The control lever 28 is pivoted by shoulder screws 32 at its lower end to a shaft member 34 mounted in bearings 36 on a bracket 38. This bracket is provided with openings 40 to receive bolts and nuts for purposes of mounting. This bracket is further provided with an extension 42 having a boss 44 to form a bearing for a secondary shaft 46. Integrally formed on one end of the shaft 46 is a lug 48 which is pivotally connected to a universal clevis 50, which in turn is pivotally connected by clevis pin 52 to link 54 that is pivotally attached to the control lever 28 at point 56 on same by shoulder screws 58. At the opposite end of the shaft 46 is mounted a lever 60 and rigidly fixed thereto by a bolt and nut connection 62 passing through the bearing portion 64 of the lever 60 and the shaft 46.

Mounted at the outer end of the shaft 34 is a lever arm 66 that is connected rigidly to the shaft 34 by bolt and nut connection 68. It will now be apparent that in moving the control lever 28 forward or backward from a normal position, as shown in Figs. 1 and 2, the lever arm 66 is simultaneously rotated in the bearing 44 through link 54, universal clevis 50 and shaft 46. Also moving the control lever laterally in either direction will cause a rocking of the shaft 34 and a corresponding movement of the lever arm 66. With this construction any movement of the control lever 28 in a direction other than backward or forward, or in a lateral direction at right angles to the backward and forward movement will effect a movement of both the levers 60 and 66, thus providing a control lever having a universal swiveling action to actuate the levers simultaneously or independently of one another.

The casing of the fluid pressure supply valve 30 is preferably made integral with the bracket 38 and is positioned directly beneath the control lever 28. Provided within this casing is a central longitudinal bore of different diameters to receive a balanced valve member that is retained in yielding position at the lower end of the casing or body by means of a coil spring 70 and flange nut 72. The valve member is provided with a tapered head 74 that bears or seats against a bushing 76 and is balanced by providing at its lower end a piston member 78 that slides in bushing 80. The valve member has extending upwardly beyond the tapered head 74 a valve stem 82 and slidably attached thereon is a spherical seat member 84.

Passing through the control lever 28 is a rod 96 provided at its lower end with a collar 88 having a frictional end surface of generally spherical shape that is frictionally held against the seat by means of a coil spring 90 mounted between the seat member 84 and a bushing 92 that is threaded into the valve body or casing 30 for retaining the packing 94 about the valve stem 82.

The rod 96 is slidably mounted within the tubu-

lar column 98 of the lever 28 and is retained in position by means of a pin 100 fixed to the rod 96. Said pin is received within an L-shaped slot 102 formed in the column 98. Threaded onto the upper end of the rod 96 is a knob 104 and held by pin 106 which forms a handle for the control lever 28. The knob is provided with a bored portion 108 to slidably receive the upper end of the column 98 and is of sufficient depth to permit a downward as well as rotary movement of the rod 96. By pressing on the knob 104 and rotating the same within the base the rod will be latched in its downward position. It will thus be seen that regardless of the position of the control lever the spherical collar 88 will constantly and frictionally engage the seat member 84 likewise any downward pressure on the knob will force the valve member down and away from the seat of the bushing 76 thereby opening supply valve to permit the fluid pressure to enter the opening 110 at the lower side of the valve seat and pass through the opening 112 at the upper side of the valve seat, and balancing the valve member by the pressure against the piston member 78.

The ailerons 12 and elevators 14 are connected to the manual control stick 16 through cables in the usual and well-known manner, as described in my above-referred-to co-pending application.

The fluid pressure control unit 24 for the ailerons is suitably mounted within the fuselage and is operatively connected to the usual aileron shaft 114 by means of the conventional rocker arm 116 and links (not shown).

The control unit 26 is likewise suitably mounted within the fuselage and is operatively connected to the usual elevator shaft 118 through the conventional rocker arm 120 and link 122.

The controller or control lever unit 22 is operatively connected to each of the operating valve devices 124 of control units 24 and 26, the operating valve device of control 24 being connected to the controller by a rod 124 that is attached at its opposite ends to levers 66 and 126, the operating valve device of control unit 26 being connected to the controller by cables 128 and 130 passing over suitable pulley and attached at their ends to the levers 60 and 132, as best shown in Fig. 5. Fluid pressure from the tank 20 is supplied to the control units by means of a fluid pressure pipe 134. This pipe is threaded into the opening 112 in the valve casing 30 and likewise connected to the openings 136 and 138 of the fluid pressure control units 24 and 26 respectively.

The control units 24 and 26 are identical in construction, and are sufficiently described in my above-referred-to co-pending application, and therefore, it will suffice for purposes of clearness to describe but one of these, and only so much thereof as will suffice for an understanding of its cooperation with the controller.

The control unit 26, as shown in Fig. 5, consists of a casing 140 containing a working cylinder 142 and a locking cylinder (not shown), both cylinders being controlled by the operating valve device 124, but inasmuch as the locking cylinder and as much of the operating valve device as cooperates with the locking cylinder is not necessary for a clear understanding of this invention, description of the control unit will be limited to the working cylinder and its cooperating parts. The working cylinder 142 is provided with a piston 144 having piston rings 146 for the usual purpose of having the piston fit cylinder closely and prevent leakage from one side to the other. The piston is provided with a control

bore to receive connecting rods 148 and 150 that are in alignment and joined together by a tap and thread connection (not shown). These piston rods 148 and 150 extend respectively through the cylinder heads 152 and 154, which are threaded into the casing 142, suitable packing and gland nuts being provided around the piston rods to prevent leakage.

The outwardly projecting ends of rods 148 and 150 are connected by yokes 156 and 158 respectively. The yoke 158 at its upper end is provided with an extension 160 which is pivotally connected to a lever 162 by a link 164.

The yokes 156 and 158 are also respectively fixed to the ends of rods 166 and 168 of a piston (not shown) by means of nuts. This cooperates with the piston of the working chamber or cylinder to lock the same in the manner described in my above-referred-to application.

20 As shown in Fig. 6 the control valve casing is provided with a cylinder at right angles to the working cylinder 142 and locking cylinder 170 and interposed between them to receive the operating valve device 124. This operating valve device 25 comprises an outer valve member 172 and inner valve member 174. The outer valve member is rotatably mounted within the cylinder and is held in place by means of a coil spring 176 seated about a reduced portion 178 thereof and is 30 retained in the pocket formed in a flanged nut 180. The reduced portion is squared at its end shoulder to receive the lever 132 which is fixed to the valve 172 by means of a nut 182.

The inner valve 174 is provided at its inner 35 end with a tapered portion to form a tapered fit with the valve 172. To the outer end of this valve 174 the lever 162 is fixed by means of a square shoulder and clamping nut 184.

As shown in Fig. 7, the outer valve member 40 172 is provided with an opening 186 that registers with an inlet opening 188 in the inner valve member 174. The opening 188 is at right angles to, and connected with openings 190 and 192 that permits the flow of fluid pressure when in an 45 opened position through the openings 194 and 196 respectively. An exhaust opening 198 likewise registers with openings 194 and 196 to relieve the flow of fluid pressure as will be herein-after described.

50 The inner and outer members, as shown in Fig. 7, are in closed position and it will be seen that when the outer member is rotated, as shown in Fig. 8, the opening 190 is uncovered to register with the opening 194 allowing the fluid pressure 55 to enter through the opening 200 from the source of supply to a passage 202 that leads into the cylinder chamber 142, on one side of the piston 144. At the same time the fluid pressure on the opposite side of the piston is relieved by the exhaust 60 port 198 on the inner valve member, registering with opening 196 on valve 172 and passage leads 204 from the cylinder 142. The exhaust opening 198 is formed by cutting a recess in the outer surface of the inner valve member 174, as shown in Fig. 6. The inner valve member is also provided with a hole 206 that connects the exhaust opening 198 to the atmosphere through opening 208. Likewise a reversal of movement imparted to the outer valve member will cause the fluid 65 pressure to flow in the opposite direction and through opening 196 and passage 204 to the cylinder and exhaust fluid pressure passing through the passage 202 and the opening 194 and exhaust port 198 as before described.

70 75 The operation of the operating valve device is

as follows: When the lever arm 132 attached to valve member 172 is at right angles to the lever arm 162 attached to valve member 174, the operating device is closed, as shown in Figs. 5 and 7, and no pressure is admitted to either side of the piston 144. In moving the lever arm 132 in a counter-clockwise direction to actuate the outer member 172, the port openings 190 and 194 will be uncovered, as shown in Fig. 8, and the fluid pressure is then admitted at opening 200 to the cylinder 142, which will move the operating piston 144 to the left, as shown in Fig. 5.

Since the lever arm 162 on the inner valve member 174 is connected to the working piston 144 by a link 164 and yoke 158, any movement of the piston 144 will in turn move the lever arm 162 on the inner valve member in the same direction as the piston until both lever arms 132 and 162 are again at right angles to each other. This likewise closes off the supply of fluid pressure to the cylinder and also holds the piston against movement at no matter what point of travel this may occur, depending entirely on the amount of movement of the lever arm 132.

20 Thus any movement of the control lever 28, 25 which simultaneously or independently operates the control units 24 and 26 and which controls the supply of fluid pressure through valve 30 to the cylinder 142, will simultaneously or independently cause a movement of the working piston of each control unit, which in turn will operate the ailerons and elevators either simultaneously or independently of one another. It will thus also be seen that movement of the working piston of either of the control units in either direction is proportionate and in synchronous relation with the movement of the control lever 28.

30 35 What I claim as new and desire to secure by Letters Patent is:

1. A controller device for controlling the fluid 40 pressure from a source of supply to at least two independent, valve controlled working chambers comprising, valve means for controlling the supply of fluid to the valves of said chambers, a support for said valve means, and means carried by said support for operating said working chamber valves simultaneously or independently of one another and for operating said valve means independently of said chamber valves.

2. A controller device adapted for controlling the fluid pressure from a source of supply to at least two independent, valve controlled working chambers comprising, valve means for controlling a supply of fluid to the valves of said chambers, a support for said valve means, and a single 50 55 manually operable member carried by said support and associated with said valve means for operating said working chamber valves simultaneously or independently of one another.

3. A controller device adapted for controlling the fluid pressure from a source of supply to at least two independent, valve controlled working chambers comprising, an inlet valve for varying the supply of fluid pressure to said chambers, a support for said inlet valve and a universal means 60 65 including a manual member for operating said working chamber valves simultaneously or independently of one another by one movement and said inlet valve by a different movement.

4. A controller device for controlling the fluid 70 pressure from a source of supply to at least two independent, valve controlled working chambers comprising, valve means for controlling a supply of fluid to the valves of said chambers, a support for said valve means, a single manually 75

operable member carried by said support and associated with said valve means for operating said working chamber valves simultaneously or independently of one another, and means for retaining said manually operable member.

5. A controller device adapted to control the fluid pressure from a source of supply to at least two independent, valve controlled working chambers comprising an inlet valve for varying the 10 supply of fluid pressure to the valves of said chambers, a support for said inlet valve having inlet and outlet conduits in communication with said inlet valve, a single manual means for operating said working chamber valves simultaneously 15 or independently of one another and said inlet valve independent of said working chamber valves and friction means between said inlet valve and said manual means for yieldingly retaining said manual means in any rocked position.

20. 6. A mechanism for controlling the fluid pressure from a source of supply to at least two working chambers comprising, a fluid supply inlet valve through which pressure is supplied to said chambers, a further valve in communication with said first-mentioned valve and associated with each chamber for controlling the communication of the fluid pressure supply thereto, and a single manually operable means for operating said communication control valves simultaneously 25 or independently of one another and for operating the fluid supply inlet valve.

7. A mechanism for controlling the fluid pressure from a source of supply to at least two working chambers comprising, a fluid supply inlet valve through which pressure is supplied to said chambers, a further valve in communication with said first-mentioned valve and associated with each chamber for controlling the communication of the fluid pressure supply thereto, and a single manually operable means for operating said communication control valves simultaneously 30 or independently of one another and for operating the fluid supply inlet valve, said manually operable means comprising two control levers movable together about either and both of two axes at right angles to one another, one of said levers being movable relative to the other along an axis at right angles to the above said axes to actuate said inlet valve independently of 35 said working chamber valves.

40. 8. A mechanism for controlling the fluid pressure from a source of supply to at least two working chambers comprising, a fluid supply inlet valve through which pressure is supplied to said chambers, a further valve in communication with said first-mentioned valve and associated with each chamber for controlling the communication of the fluid pressure supply thereto, and a single manually operable means for operating said communication control valves simultaneously 45 or independently of one another and for operating the fluid supply inlet valve, said manually operable means comprising two control levers movable together about either and both of two axes at right angles to one another, one of said levers being movable relative to the other along an axis at right angles to the above said axes to actuate said inlet valve independently of 50 said working chamber valves and means between said levers for locking said inlet lever in an operative position thereof.

75. 9. A controller unit adapted for controlling the fluid pressure from a source of supply to at least two working chambers comprising, a support for

an inlet valve provided with a valve seat, a valve stem seated against said valve seat, a universally mounted lever carried by said support, for separately controlling said working chambers and a lever carried by said first-mentioned lever and operable independently thereof for controlling said inlet valve in any position of said first lever.

5. 10. A controller unit adapted for controlling the fluid pressure from a source of supply to at least two valve controlled working chambers comprising, a support for an inlet valve provided with a valve seat, a valve stem seated against said seat, a universally mounted lever carried by said support for controlling said working chambers, and an inlet valve operating member movable with said lever but capable of relative sliding motion with respect thereto for operating said inlet valve independently of said working chamber valves.

20. 11. A controller unit adapted for controlling the fluid pressure from a source of supply to at least two working chambers comprising, a support for an inlet valve provided with a valve seat, a valve stem seated against said seat, a universally mounted lever carried by said support for controlling the fluid supply to said chambers, and a valve operating member movable with said lever but capable of relative sliding motion with respect thereto for operating said inlet valve in any position of said universal lever and independently of the operation of the latter lever.

25. 12. A control mechanism, comprising in combination, a support, control means, universal means interconnecting said support and said control means, valve means operated by a relative movement of said control means and said universal means, means between said valve means and said control means to permit tilting of said control means without actuating said valve means 30 and for retaining the same in any tilted position of the latter, and further means between the universal means and said control means for maintaining the latter in its valve operated position.

35. 13. The combination with a control lever mounted so that it can rock about either and both of two axes at right angles to one another and a further control lever carried by said first lever and mounted so that it can move independently of said first lever along a third axis at right angles to said first axes, of means cooperating with said levers respectively for fixing the same in every operative position thereof.

40. 14. The combination with a control lever mounted so that it can rock about either and both of two axes at right angles to one another and a further control lever carried by said first lever and mounted so that it can move independently of said first lever along a third axis at right angles to said first axes, of means between said levers for locking said second mentioned lever in operated position.

45. 15. The combination with a control lever mounted so that it can rock about either and both of two axes at right angles to one another and a further control lever carried by said first lever and mounted so that it can move independently of said first lever along a third axis at right angles to said first axes, of yieldable engaging means for fixing said first-mentioned lever in any moved position thereof and mounted so as to be responsive to an operative movement of said second-mentioned lever, said engaging means and said latter lever being relatively dis- 70

placeable to permit operative movement of said first-mentioned lever irrespective of the operative movement of the second-mentioned lever.

16. The combination with a control lever mounted so that it can rock about either and both of two axes at right angles to one another and a further control lever carried by said first lever and mounted so that it can move independently of said first lever along a third axis at right angles to said first axes, of spring actuated friction engaging means for fixing said first-mentioned lever in any moved position thereof and mounted so as to be responsive to an operative movement of said second-mentioned lever, said engaging means and said latter lever being relatively displaceable to permit operative movement of said first-mentioned lever irrespective of the operative movement of the second-mentioned lever.

17. In combination a control lever mounted so that it can rock about either and both of two axes at right angles to one another and a further control lever carried by said first lever and mounted so that it can move independently of said first lever along a third axis at right angles to said first axes, valve means adapted to be actuated by a linear movement of said second-mentioned lever and means between said valve means and said second-mentioned lever for slideable and yieldable engagement with said latter lever whereby said first-mentioned lever may be rocked about its axes in every operative position of said second-mentioned lever.

18. In combination a control lever mounted so that it can rock about either and both of two axes at right angles to one another and a further control lever carried by said first lever and mounted so that it can move independently of said first lever along a third axis at right angles to said first axes, valve means adapted to be actuated by a linear movement of said second-mentioned lever and a friction element disposed between said valve and one end of said second-mentioned lever and spring means for effecting a yieldable engagement between said friction element and the end of said lever.

19. In combination a control lever mounted so that it can rock about either and both of two axes at right angles to one another and a further control lever carried by said first lever and mounted so that it can move independently of said first lever along a third axis at right angles to said first axes, valve means adapted to be actuated by linear movement of said second-mentioned lever and a friction element having a concave special surface disposed between said valve and one end of said lever and spring means for effecting a yieldable engagement between said friction element and the end of said lever.

20. A control unit adapted for controlling the fluid pressure from a source of supply to a valve controlled working chamber comprising a support for an inlet valve provided with a valve seat, a valve stem seated against said valve seat, a universally mounted lever carried by said support for controlling said working chamber valve, and a lever carried by said first-mentioned lever and operable independently thereof for control-

ling said inlet valve in any operative position of said first-mentioned lever.

21. A control device for controlling the fluid pressure from a source of supply to a working chamber comprising, in combination, a fluid supply inlet valve, a valve for said chamber, and a manual control means comprising a pivoted lever for actuating said working chamber valve and a lever movable with said pivoted lever but operable independently thereof for actuating said supply valve.

22. A control device for controlling the fluid pressure from a source of supply to a working chamber comprising, in combination, a fluid supply inlet valve, a valve for said chamber, a manual control means comprising a pivoted lever for actuating said working chamber valve and a lever movable with said pivoted lever but operable independently thereof for actuating said supply valve, and means interposed between said inlet valve and its corresponding lever to permit operation of one lever independently of the other and vice versa.

23. A control device for controlling the fluid pressure from a source of supply to a working chamber comprising, in combination, a fluid supply inlet valve, a valve for said working chamber, a manual control means for actuating said valves, said control means comprising two levers movable together and one independent of the other and being so constructed and arranged that each lever is capable of operating its corresponding valve independently of the other in operative or inoperative position of said valves.

24. A control device for controlling the fluid supply from a source of supply to a plurality of working chambers comprising, in combination, a fluid supply inlet valve, a valve for each of said chambers, and a manual control means comprising a pivoted lever movable to different positions for actuating said working chamber valves and a lever movable with but operable independently of said pivoted lever for actuating said supply valve in any position thereof.

25. A control device for controlling the fluid supply from a source of supply to a working chamber comprising, in combination, a fluid supply inlet valve, a valve for said chamber, a manual control means comprising a pivoted lever for actuating said working chamber valve and a lever movable with said pivoted lever for actuating said supply valve, and means interposed between said inlet valve and its corresponding lever adapted for relative displaceable operative connection between said supply valve and its corresponding lever.

26. A control device for controlling the fluid supply from a source of supply to a working chamber comprising, in combination, a fluid supply inlet valve, a valve for said chamber, and a lever for operating each valve, said levers being so constructed and arranged with respect to each other and their respective valve connections that both levers are operable in unison to operate one of said valves and one of said levers is operable independent of the other in any position thereof to operate the other valve.

ERNEST G. McCauley.
